180,634

PORTABLE COMMODE

Robert H. Zoffer, Brooklyn, N. Y.

Application May 25, 1954, Serial No. 30,641

Term of patent 14 years

(Cl. D4—5)

FIG.2.

FIG.1.

FIG. 4.

FIG.3.

Fig. 1 is an elevational view of a portable commode, showing my new design.

Fig. 2 is a top plan view thereof.

Fig. 3 is a fragmentary enlarged sectional view taken along line 3—3 of Fig. 2.

Fig. 4 shows in exploded form, the commode, the intermediate seat portion and the cover thereof.

I claim:

The ornamental design for a portable commode, substantially as shown.
